UNITED STATES PATENT OFFICE.

JOHN ROBERTS, OF ELMIRA, NEW YORK, ASSIGNOR OF ONE-HALF TO CAROLINA ROBERTS, OF WHITE HAVEN, PENNSYLVANIA.

TRACK CONSTRUCTION.

Application filed October 22, 1921. Serial No. 509,470.

To all whom it may concern:

Be it known that I, JOHN ROBERTS, a citizen of the United States, residing at Elmira, in the county of Chemung and State of New York, have invented new and useful Improvements in Track Constructions, of which the following is a specification.

My present invention has reference to a railroad track construction.

10 My primary object is to produce a novel means for supporting the rails of a track without the employment of spikes or analogous devices and in which the rails may be properly adjusted with respect to each other 15 so that either a wide or narrow gauge track may be provided.

A further object is to produce, in a track construction, metal ties having adjustably secured thereon longitudinally arranged casings arranged in spaced pairs, each of said casings having movable therethrough a bolt or key member designed to be brought into wedging engagement with the base flanges of the rails and locked in such engagement, 25 whereby the rails will be prevented from tilting or vertical movement, the construction being such however, as to permit of the necessary longitudinal movement of the rails incident to expansion and contraction.

30 The foregoing, and other objects which will appear as the nature of the invention is better understood, may be accomplished by a construction, combination and operative association of parts such as is disclosed by 35 the drawings which accompany and form part of this specification.

In the drawings:—

Figure 1 is a plan view of the main and side lines of a railway track in which the 40 rails thereof are supported on ties in accordance with this invention.

Figure 2 is a sectional view upon a greatly enlarged scale and approximately on the line 2—2 of Figure 1.

45 Figure 3 is a sectional view, also on an enlarged scale, and approximately on the line 3—3 of Figure 1.

Figure 4 is a perspective view of one of the ties.

50 Figure 5 is a similar view of another form of tie.

Figure 6 is a perspective view of one of the lock casings.

Figure 7 is a similar view of the bolt or key slidable through the casing. 55

Figure 8 is a sectional view on the line 8—8 of Figure 1.

As disclosed in Figure 1 of the drawings, the ties 1 vary in length as certain of the ties support thereon the rails of both the main line and the siding. However, in each instance the ties are constructed of metal, and except when the ties are employed on bridge or trestle works, the same are centrally formed with a depending longitudinally extending centrally arranged rib 2. The flat ties are indicated by the numeral 3 and are bolted, spiked, or otherwise secured to the trestle works, while the ribs 2 of the ties 1 are embedded in the road bed. Thus 70 the ribs will hold the ties against tilting, sinking or longitudinal movement. If desired, the ties, at the ends thereof may be provided with openings through which may pass spikes 4 which enter the road bed and 75 assist in holding the ties from moving longitudinally.

All of the ties are provided at a suitable distance inward from their edges and at suitable distances from their ends with longitudinally extending slots 5. These slots are arranged in spaced aligned pairs near each end of the ties, and the space between the pairs of slots approximately equals the width of the base flanges 6 of the rails 7. 85 Over the pairs of slots on each of the ties there are arranged flat base portions 8 of casings 9. The base portions 8 of the casings have bolt openings therethrough and bolts 10 pass through the slots 5 in the tie and 90 through the said openings in the base portions, the said bolts being engaged by nuts 11 which in turn contact with and press against the upper faces of the base portions of the casings and split spring washers 12. 95

The casings 9 are thus capable of sliding movement on the ties approximately the length of the slots when the nuts are loosened on the bolts 10. A bolt 13 is mounted in the casing 9 and has a threaded hole therein adapted to register with an opening in the top of the casing to receive a screw or bolt 15 100

to maintain the bolt in position within the casing. Each bolt or key has its inner or confronting end beveled as at 14 to correspond to the angular cross sectional contour 5 of the upper portion of the base flanges of the rails.

It is believed that the foregoing description, when taken in connection with the drawings will amply set forth the construction and advantages of the improvement to 10 those skilled in the art to which this invention relates, it being understood that the slots in the ties permit of a longitudinal movement of the lock casings thereover so 15 that the ties may be employed for supporting the rails of either a narrow or wide gauge track. It will be also understood that by actuating the locking means for the bolt, to unlock position, the bolts or keys may 20 be moved through the casings out of rail engagement, and while I have illustrated and described the said embodiment of the improvement as it now appears to me, it is to be understood that I am not to be restricted 25 to the details of construction herein referred

to and illustrated, but am entitled to such departures therefrom as fall within the scope of what is claimed.

Having described the invention what is claimed is:—

1. In combination with a tie plate having spaced slots therein, a casing having outwardly extending base flanges mounted over the slots, a bolt mounted in the casing adapted to engage a track rail, and means securing 35 said casing to the tie through the slots therein.

2. In combination with a tie plate having a pair of spaced parallel slots at each end, a casing including a hollow central portion 40 and base members extending from said central portion, said base members being disposed over the slots in the ties, a bolt mounted in the casing for engagement with a track rail, and means mounted through said slots 45 and base members slidably connecting the casing with the tie.

In testimony whereof I affix my signature.

JOHN ROBERTS.
